UNITED STATES PATENT OFFICE.

FRANK C. DE REAMER, OF SCHENECTADY, NEW YORK, ASSIGNOR TO GENERAL ELECTRIC COMPANY, A CORPORATION OF NEW YORK.

TWO-BUTTON PENDENT SWITCH.

980,926.

Specification of Letters Patent. Patented Jan. 10, 1911.

Application filed October 2, 1907. Serial No. 395,538.

To all whom it may concern:

Be it known that I, FRANK C. DE REAMER, a citizen of the United States, residing at Schenectady, county of Schenectady, State of New York, have invented certain new and useful Improvements in Two-Button Pendent Switches, of which the following is a specification.

This invention relates to mechanical cut-outs for electric circuits, and its object is to apply the principles of a two-button wall-switch to a structure capable of use as a drop or pendent switch. For the sake of compactness, the switch is of the single-pole type, and the movable blade acts as a bridging contact between two stationary contacts. The particular features of novelty will appear from the following detailed description and claims.

20 In the accompanying drawing, Figure 1 is a longitudinal sectional elevation of a switch embodying my improvements; Fig. 2 is a longitudinal sectional elevation on a plane at right-angles to Fig. 1; Fig. 3 is a 25 perspective view of an insulating shield; Fig. 4 is a view on a larger scale of the operating parts; Fig. 5 is a similar view after the switch-blade has moved; and Fig. 6 is an end view of the body.

30 The base or body portion 1 is made of 35 molded insulating material, such as porcelain, and is preferably cylindrical in shape. It has a central longitudinal opening or slot 2 with longitudinal grooves 3-4 on each side, respectively, extending up from the lower end of said body. This body is incased in a metallic shell composed preferably of an upper half 5 and a lower half 6 connected in any suitable manner. The upper 40 half is lined with insulation 7, and has a central aperture provided with an insulating bushing 8, through which the conducting and suspending insulated conductors 9 enter the casing. The bared ends of these conductors are respectively connected by binding-screws 10 to two plates 11 secured to the upper end of the body on opposite sides of the seat 2 near one side of said body, and each provided with a resilient finger 12 45 which depends into said slot.

The switch-blade 13 has a transverse head 14 whose ends are adapted to make contact with the fingers 12 and electrically connect them when the blade is moved to a position 50 between them. When the head 14 is swung

to the other side of the body 1, the circuit will be opened. The lower end of the switch-blade is pivoted at 15 to the lower end of a hanger 16 which has a flange 17 secured to the body at the upper end of the 60 groove 3. A curved seat 18 is cut in said hanger concentric with the pivot 15 of the switch-blade, and a lug 19 on said blade projects through said slot and plays freely back and forth therein, as the switch-blade swings 65 to and fro.

A stud 20 is fixed in the hanger somewhat above the pivot 15. One end extends into the groove 3 and the other projects through a curved slot 21 in the switch-blade into the 70 groove 4. On this stud, between the switch-blade and the hanger, is loosely pivoted a yoke 22, to the ends of which are pivoted the stems 23 of the push-buttons 24-25 which ride in the lower portion of the slot 2 and 75 project through holes in the lower end of the casing. On this yoke is a laterally-projecting lug 26 extending through the slot 18 in the hanger just below the lug 19 on the switch-blade. A helical spring 27 is 80 coiled on the stud 20 behind the hanger, and its straight ends bear against the opposite sides of the two lugs 19-26, tending to keep them in line with each other.

The adjacent faces of the switch-blade 85 and yoke are each provided with a locking lug, the two lugs being adapted to coöperate with each other. Thus, when the parts stand as shown in Fig. 1, the lug 28 on the yoke is inside of the lug 29 on the switch-blade, but when the button 25 is pushed in and the parts move to the position shown in Fig. 5 the lug on the yoke will be the outside one; owing to the fact that the lug 28 moves in an up and down direction, while 90 that on the switch-blade moves in a substantially transverse direction.

The operation is as follows: When the switch is open, the parts stand as shown in Fig. 1. To close it, the button 25 is pushed 100 in, which rocks the yoke to the position shown in Fig. 4. The switch-blade, however, cannot move, because its lug 29 is locked by the lug 28 on the yoke. The movement of the yoke separates the straight 105 portions of the spring, putting it under greater tension, and the lugs are gradually moved out of line, until, at the instant the tip of the lug 28 clears the lug 29, the blade is thrown over suddenly by the spring to the 110

position shown in Fig. 5. The head 14 enters between the resilient fingers 12 and closes the circuit. In opening the switch, the lug 28 passes down outside of the lug 29, 5 and locks the blade from moving until the spring is ready to snap it over quickly.

In order to protect the conductors 9 from injury by arcs formed at the contacts, a shield is placed over said contacts, consisting preferably of a sheet 30 of insulation having tongues 31 at each end adapted to engage with lips 32 at the ends of the slot 2, as shown in Fig. 1.

What I claim as new, and desire to secure by Letters Patent of the United States, 15 is,—

1. A two-button pendent switch comprising a body of insulation having a longitudinal slot extending therethrough and grooves 20 on opposite sides of said slot extending in from the bottom toward the top, resilient contact fingers depending into said slot at the upper end and on opposite sides of said slot near one side of said body, a hanger in 25 one of said grooves, a switch-blade pivoted to said hanger and having a head adapted to connect said fingers, a yoke pivoted to said hanger above the pivot of the switch-blade, push-buttons depending from the 30 ends of said yoke through the lower end of said slot, and operative and locking connections between said yoke and switch-blade.

2. In a switch, the combination of a body of insulation having a slot extending therethrough and grooves on opposite sides of said slot extending from the bottom toward the top, a hanger having a bent end secured thereto at the upper end of one of said grooves, a stud mounted transversely in said 40 hanger and having its ends disposed in said grooves, stationary contacts secured to the upper end of said body, and a movable contact and actuating means carried by said hanger.

3. In a switch, the combination of a body of insulation having a slot extending therethrough and a groove on one side of said slot extending from the bottom toward the

top, a hanger secured at the upper end of said groove and provided with an aperture, 50 a switch-blade pivoted on the front side of said hanger and provided with a bent part projecting through said aperture and adapted to engage the ends thereof, a stud mounted in said hanger above the pivot of 55 the switch-blade, a yoke pivoted on said stud adjacent said pole piece and provided with a bent part projecting through said aperture, a double-ended spring carried by said stud at the back of the hanger with its 60 ends disposed on opposite sides of said projections, and a lug on said switch-blade directly engaging a lug on said yoke and operating to prevent movement of the switch-blade during tensioning of the spring by 65 movement of said yoke.

4. In a switch, the combination of a hanger, a switch-blade pivoted on the front side of said hanger and having a bent part projecting to the back of said hanger, a 70 stud mounted in said hanger above the pivot of the switch-blade, a yoke pivoted on said stud between said hanger and switch-blade and having a bent part projecting to the back of the hanger parallel to the bent part 75 of the switch-blade, a double-ended spring carried by the said stud at the back of the hanger with its ends disposed on opposite sides of said bent parts, and lugs on said switch-blade and said yoke adapted to engage each other and prevent movement of the switch-blade during the tensioning of the spring by movement of the said yoke.

5. The combination with a body of insulation having a slot extending therethrough and provided with lips at the upper end, binding posts secured to the upper end of said body, and a sheet of insulation having slits in its ends to form tongues adapted to engage said lips.

In witness whereof, I have hereunto set my hand this 30th day of September, 1907.

FRANK C. DE REAMER.
